CLAIM

The ornamental design for the automobile lower grille, as shown and described.

DESCRIPTION

FIG. 1 is a top perspective view of the automobile lower grille of the present invention;

FIG. 2 is a bottom perspective view thereof;

FIG. 3 is a front elevation view thereof;

FIG. 4 is a rear elevation view thereof;

FIG. 5 is a top view thereof;

FIG. 6 is a bottom view thereof;

FIG. 7 is a right side view thereof;

FIG. 8 is a left side view thereof; and,

FIG. 9 is a perspective view thereof in an exemplary automobile.

The broken lines are provided for the purpose of illustrating environmental structure(s) and form no part of the claimed design.

1 Claim, 6 Drawing Sheets
